UNITED STATES PATENT OFFICE.

FREDERICK LANGLEY AND GEORGE B. LAUNDRIE, OF ROUSES POINT, NEW YORK.

GAME.

1,033,422.

Specification of Letters Patent.

Patented July 23, 1912.

Application filed October 23, 1911. Serial No. 656,188.

To all whom it may concern:

Be it known that we, FREDERICK LANGLEY and GEORGE B. LAUNDRIE, residing at Rouses Point, county of Clinton, and State of New York, have invented a new and Improved Game, of which the following is a specification.

Our invention relates to that class of games or puzzles in which, without knowledge of the exact manipulation of the parts, the act of playing the game is amusing and puzzling and the said invention consists in the novel arrangement of the parts as will be hereinafter fully explained, pointed out in the claims and illustrated in the accompanying drawings, in which:

Figure 1, is a plan view of our game, the parts being in position to be worked. Fig. 2, is a plan view of the game-board with the pegs removed. Fig. 3, is a cross section of the same on the line 3—3 on Fig. 1.

In the practical arrangement, our invention comprises a bottom board 100 having a surrounding vertically extended ledge 110 and provided with a series of sockets 1 to 37 inclusive of like diameter for snugly receiving pegs 103, of which there are as many as the sockets less one, whereby when all of the pegs are set a single one 19 of the 30 holes or sockets remains open, which in the solving or playing of our puzzle game must be the central socket designated 19.

In playing our game, the idea is in the setting of all of the pegs by placing a peg into each socket except the central one 19 and then, by jumping from any of the four sides of the central socket removing the pegs that are jumped and contriving to jump one peg at a time until only a single peg is left 40 and that located in the central socket 19.

In our game board the holes or sockets are relatively arranged with respect to each other that the game can only be successfully played by making the jumps diagonal and straight, and to provide for such a result we arrange the holes or sockets into three central parallel rows of seven sockets, a supplemental row of five sockets one at each side of the rows of seven sockets, and in 50 parallelism and then another row of three sockets next to the five sockets and in parallelism therewith, the arrangement of the holes or sockets presenting two sets of three rows of seven sockets, arranged crosswise, 55 and a supplemental hole, designated 4, 8, 30 and 34, at the four outside angles of the two crossed sets of rows of seven sockets.

The pegs 103 include tenons 130 that snugly fit down into the sockets, and head portions 131 which may be ornamental or if desired 60 suitably embellished by numbers or letters so that, when set, will spell a desired word or words, for example, the name of the game.

By reason of the arrangement of the holes 65 and pegs it is impossible to successfully solve our puzzle game without making certain straight and diagonal jumps since by making straight jumps only in either direction, it will be impossible to land the final 70 peg in the central socket.

We are aware that games in which is used a socketed board and pins have been heretofore provided but so far as we know the arrangement of the sockets have been 75 such that the game must be played by straight jumps only and in which diagonal jumps are not permitted, and if made, would not solve the game.

The ledge 110 in our construction of game 80 extends up sufficiently to hold the loose pegs from rolling off the board but does not interfere with the convenient or ready fingering of the pegs in playing the game and furthermore the said peg bodies project above 85 the upper edge of the said ledge when lying down whereby to facilitate the ready gripping of the pegs with the fingers when they are wanted to fill the sockets.

The solution of our puzzle can be effected 90 by the following moves:

Move #1	Move #2	Move #3	Move #4
34 to 19	15 to 27	29 to 15	8 to 21
Move #5	Move #6	Move #7	Move #8 95
33 to 22	15 to 29	20 to 33	37 to 27
Move #9	Move #10	Move #11	Move #12
19 to 8	29 to 13	32 to 21	6 to 19
Move #13	Move #14	Move #15	Move #16 100
21 to 6	25 to 13	8 to 19	35 to 37
Move #17	Move #18	Move #19	Move #20
24 to 36	3 to 13	13 to 25	2 to 12
Move #21	Move #22	Move #23	Move #24 105
37 to 35	18 to 31	9 to 25	30 to 19
Move #25	Move #26	Move #27	Move #28
35 to 25	19 to 32	23 to 9	32 to 17
Move #29	Move #30	Move #31	Move #32 110
17 to 6	9 to 11	1 to 9	12 to 10
Move #33	Move #34	Move #35	
6 to 4	9 to 11	4 to 19	

What we claim is:

1. In a game apparatus, a game board having two sets of rows of sockets, one set crossing the other set, and supplemental 5 sockets disposed adjacent to the corners formed by the crossing rows and a set of pegs one less than the total number of sockets.
2. In a game apparatus, a game-board 10 having sockets, pegs for entering the said sockets, said pegs having enlarged finger engaging heads and a ledge around the said board and projecting above the plane of the socketed face of the said board a distance 15 less than the dimensions of the peg heads to cause said peg heads to project above the said ledge when lying on the board as well as when in the sockets.
3. A game of the character stated comprising a base board having sockets, said 20 sockets being arranged in three parallel sets of rows of seven each, two rows of five, one at each side of the set of rows of seven sockets and two rows of three, one adjacent each row of five sockets; the rows of five 25 and three sockets being in parallel with the rows of seven sockets and a set of pegs for fitting the sockets one less than the total number of the sockets.

FREDERICK LANGLEY.
